DESIGN FOR A CLOTHING HOOK

Viktor Keller, New York, N. Y.

Application January 30, 1941, Serial No. 98,533

Term of patent 3½ years

To all whom it may concern:

Be it known that I, Viktor Keller, a citizen of Germany, residing at New York, in the county of Bronx and State of New York, have invented a new, original, and ornamental Design for a Clothing Hook, of which the following is a specification, reference being had to the accompanying drawing, forming a part thereof.

Figure 1 is a perspective view of a clothing hook; Figure 2 is a side elevation of the same; Figure 3 is a front elevation of the same; and Figure 4 is a plan view of the same, showing my design.

I claim:

The ornamental design for a clothing hook, as shown.

VIKTOR KELLER.
